UNITED STATES PATENT OFFICE.

ROBERT E. BOURKE AND HENRY WITTEKIND, OF CHICAGO, ILLINOIS.

DRINKING-RECEPACLE.

SPECIFICATION forming part of Letters Patent No. 747,123, dated December 15, 1903.

Application filed February 20, 1903. Serial No. 144,185. (No model.)

To all whom it may concern:

Be it known that we, ROBERT E. BOURKE and HENRY WITTEKIND, citizens of the United States, residing at Chicago, county of Cook, 5 State of Illinois, have invented a certain new and useful Improvement in Drinking-Receptacles; and we declare the following to be a full, clear, and exact description of the invention, such as will enable others skilled in the 10 art to which it pertains to make and use the same, reference being had to the accompanying drawings, which form a part of this specification.

Our invention relates generally to drinking-receptacles, and more particularly to a trick device from which the liquid can only be drawn by one familiar with the construction of the receptacle.

The primary object of our invention is to 15 provide a drinking-receptacle of apparently ordinary construction which when placed to the lips of the uninitiated permits the liquid to flow through openings below the rim thereof and will only deliver the contents there- 25 from to the mouth of a user familiar with its construction.

A further object of our invention is to provide a drinking-receptacle simple in construction, inexpensive in manufacture, and 30 capable of affording amusement in use.

Our invention, generally described, consists in a drinking-receptacle having one or more perforations through the wall thereof at points below its rim and provided with a 35 passage leading from the interior thereof near the bottom and communicating with the exterior of the receptacle at a point in its rim and having a port connecting said passage with the atmosphere at some point intermediate of the bottom and rim of the receptacle.

Our invention will be more fully described hereinafter with reference to the accompanying drawings, in which the same is illustrated as embodied in a convenient and practical 40 form, and in which—

Figure 1 is an elevational view; Fig. 2, a sectional view on line 2 2, Fig. 1; and Fig. 3, a sectional view on line 3 3, Fig. 1.

Similar reference characters are used to indicate similar parts in the several figures of the drawings.

A designates a drinking-receptacle of any

desired size and shape—such, for instance, as a beer-stein.

B designates the handle for facilitating the 55 use of the stein, which extends from a point near the bottom thereof to the rim C, to which the mouth of the user would ordinarily be placed to drink the contents of the receptacle.

D indicates an ornamental groove or an- 60 nular recess formed around the receptacle at a point immediately below the rim C. A series of perforations d' d' extend through the wall of the receptacle at points around the ornamental groove D. Between the suc- 65 cessive perforations d' are preferably indicated other perforations d², presenting the same appearance to the eye of the casual observer as do the perforations d', thereby creating the impression that the perforations d' are 70 merely superficial ornamentations.

A passage b leads from a point b' near the bottom of the receptacle to the rim thereof. This groove may conveniently be formed in the handle B, as indicated in the drawings. 75 The passage b is continued in the rim C of the receptacle to a point b², where it terminates at the exterior surface of the rim. The portion of the passage b in the rim C prefer- 80 ably extends toward the right a comparatively short distance from the juncture of the top of the handle with the rim of the receptacle. A port b² leads from the passage b to the at- 85 mosphere at some point intermediate of the ends of the passage. The atmospheric port b² may be conveniently located on the under side of the upper end of the handle adjacent to the rim of the receptacle.

The use and operation of our invention are as follows: When the receptacle is raised to 90 the mouth of the user and his lips placed upon the rim C, an inclination of the receptacle such as would in an ordinarily-constructed device cause the liquid contained therein to flow into the mouth of the user results in the liquid pass- 95 ing through holes d' in the receptacle below the rim, thereby preventing the liquid from flowing to the mouth of the user. The liquid flowing through the perforations d' will fall upon the clothing of the uninitiated user, much to 100 his discomfiture and the amusement of those familiar with the construction of the trick receptacle. Any one possessing a knowledge of the construction of the receptacle may

readily drink therefrom by lifting the same in the left hand and placing the lips over the opening b^3 , in which the passage b terminates, and at the same time placing a finger or 5 thumb over the atmospheric port b^2 . The liquid may then be drawn from the bottom of the receptacle through the passage b into the mouth of the user without necessitating any inclination of the receptacle such as 10 would permit the liquid to flow through the perforations d' .

The arrangement of the perforations d' and the location of the atmospheric port b^2 and the termination b^3 of the passage may be 15 such that the fact that the receptacle is anything more than of ordinary construction can only be discerned by a careful inspection thereof. One familiar with the construction 20 of the receptacle can, therefore, readily drink therefrom without disclosing the fact that it is of special construction, and even after an uninitiated person has attempted to drink therefrom he may be considerably mystified by the facility with which one familiar with 25 the receptacle may imbibe of the liquid contained therein.

It is obvious that the passage leading from the bottom of the receptacle to the rim thereof may be utilized in the same manner that 30 a straw is used in an ordinarily-constructed receptacle, and consequently our invention is useful in addition to its utility as a trick device. For such legitimate use the port to the atmosphere b^2 may be omitted.

35 From the foregoing description it will be observed that we have invented a drinking-receptacle so constructed as to have the appearance of an ordinary receptacle, but from which the contents will not flow in the cus- 40 tomary manner, but may only be imbibed by

one possessing a knowledge of its secret construction.

While we have described more or less precisely the details of construction, we do not wish to be understood as limiting ourselves 45 thereto, as we contemplate changes in form, the proportion of parts, and the substitution of equivalents as circumstances may suggest or render expedient without departing from the spirit of our invention. 50

Having now fully described our invention, what we claim as new, and desire to secure by Letters Patent, is—

The combination with a drinking-receptacle, of a circular outwardly-projecting rim 55 surrounding the top thereof, an outwardly-projecting rib formed on and surrounding the exterior surface of the receptacle and located a comparatively short distance below said rim, said receptacle having an ornamental 60 annular groove located between said rim and said rib, and having located within said groove a series of perforations extending through the wall of the receptacle, a handle for lifting the receptacle provided with a passage leading from the interior of the receptacle near the bottom thereof through the handle and terminating at an exterior point in the rim of the receptacle adjacent to the 65 top of the handle, said passage having a port leading downwardly from a point on the under side of the handle near the top thereof and communicating with the atmosphere. 70

In testimony whereof we sign this specification in the presence of two witnesses.

ROBERT E. BOURKE.
HENRY WITTEKIND.
